UNITED STATES PATENT OFFICE.

LEE S. CHADWICK, OF SHAKER HEIGHTS VILLAGE, OHIO, ASSIGNOR TO THE CLEVELAND METAL PRODUCTS COMPANY, OF CLEVELAND, OHIO, A CORPORATION OF OHIO.

STOVE.

Application filed April 25, 1923. Serial No. 634,417.

To all whom it may concern:

Be it known that I, LEE S. CHADWICK, a citizen of the United States, residing at Shaker Heights Village, in the county of Cuyahoga and State of Ohio, have invented a certain new and useful Improvement in Stoves, of which the following is a full, clear, and exact description, reference being had to the accompanying drawings.

10 This invention relates to stoves, and it has to do more particularly with liquid fuel stoves especially of the so-called "knock-down" variety which are usually constructed of sheet metal, the term "knock-down" referring to a construction which may be readily disassembled, as for shipment and storage.

The objects of the invention are to provide a stove structure incorporating a base 20 having an opening above which a burner is situated and beneath which a tray is removably supported in a position to catch any boiled over food, dirt, oil which may drain from the burner or char which may drop 25 from the wick; to provide suitable guides beneath the base for properly supporting the tray yet allowing convenient removal thereof; to provide guides for the aforesaid purpose which normally repose, preferably 30 through gravity, in operative position but which may be shifted or folded within the element of the stove structure by which they are carried to the end that the same may be made compact for shipment or storage; to provide means for rigidly sustaining 35 the burner from the stove base and which is of such a nature that oil which runs down the burner will not follow said supporting means to the top surface of the base but will 40 be diverted to the tray that is supported therebelow; and to provide a very rigid and strong stove construction through which the foregoing objects are attained and which is comparatively economical of manufacture.

45 The objects above enumerated, with others hereinafter appearing, are attained in the construction illustrated in the accompanying drawings wherein Fig. 1 is a front elevation of a liquid fuel stove incorporating my invention; Fig. 2 is a sectional plan on the line 2-2 of Fig. 1; Fig. 3 is a longitudinal section through the stove structure in the region of the base and shows the tray supported by the guides from the base; Fig. 4

is a similar view showing the legs and 55 burner tray removed and the guides folded into the base; Fig. 5 is a section on the lines 5-5 of Figs. 1 and 3; Fig. 6 is a sectional detail on the line 6-6 of Fig. 3; Fig. 7 is a detached perspective view of one of the 60 guides and the tray; Fig. 8 is a sectional detail of the burner support including the means for deflecting into the tray any oil 65 which drains from the burner; Fig. 9 is a section on the line 9-9 of Fig. 8; Fig. 10 is a perspective view of the deflector that is 70 incorporated in the burner support; and Fig. 11 is a view, similar to Fig. 8, of an alternative form of burner support.

The stove structure, generally, comprises 75 a top 1 and pan 2 that are supported at their four corners by legs 3. The connections between the top 1, pan 2 and legs 3 may be of any approved nature which enables the parts to be readily connected and disconnected 80 for the purpose of assembly or disassembly. In fact, in these respects, the structure may follow the usual practice in the construction of "knock-down" stoves.

The stove base is designated 5 and the 85 same is shown as formed of sheet metal with a peripheral flange 6 having the lower edge portions of its front, rear and end sections turned upwardly, as shown at 7, and a bar 8 extends along the inner side of the front section of the peripheral flange 6 for the purpose of imparting stability to the structure. The base is detachably connected to the legs 2 by bolts 10.

While the stove structure may be of a 90 size to accommodate any desired number of burners, I have, for convenience, shown a two burner stove, the right hand burner, as the stove is viewed in Fig. 1, being of the ordinary size, while the left hand one is a so-called "giant" burner. The burners are designated 12. Below each burner the base 5 has an opening 13. To stiffen the base about the openings and improve the appearance thereof the material of the base is 100 flanged downwardly about said openings.

At its forward side each burner is supported from the base through an adjustable leg that is made up of a part 15 which depends from the burner, and a part 16 which 105 interlocks by a tongue 17 with a slot 18 of the base, the parts overlapping and being drawn together by a bolt 19 that is engaged

through an opening in the part 16 and a slot in the part 15. Interposed between the parts 15 and 16 is a deflector 20, shown in perspective in Fig. 9, which is flared at its upper end and directed rearwardly at its lower end and provided with a bead 21 which extends over and downwardly about the upper end of a slot 22 through which the bolt 19 passes. From this construction it will be seen that any oil dripping from the burner and flowing down the part 15 will be caught by the deflector 20 and prevented from coming into contact with the part 16 or the bolt 19 through either of which it might ultimately reach the top surface of the base 5.

The space between the top 1 and base 5 is closed at each end by a panel 21 and at the rear by a back wall 22.

A fluid fuel supply pipe 25 leads from a fuel reservoir 26, that is supported from and beyond one end of the stove, through an aperture in the adjacent end panel 21 lengthwise across the base and through an aperture in the opposite end panel, the pipe 25 being clamped to ledges 32 that are secured to the end panels. The rear sides of the burners 12 are supported from the pipe 25 by elbow fittings 34 through which the burners have communicative connection with the pipe. Clamps 36 bind the fittings to the pipe in accordance with common practice.

A tray 40 is removably supported below the base 5 by tray supporting members or guides 41. Each guide is composed of an angle bar to the ends of which extensions or arms 42 are secured, said arms being shown as identical, and the connection between the arms and the angle bar may be effected by spot welding. Perforated offset portions 43 of the arms are pivotally supported upon the inner ends of screws 45 which are extended through apertures in the front and rear portions of the peripheral flange 6, and screws being held in place by nuts 46. It will be observed, especially from Fig. 6, that the arms 42 are outside the nuts so that there will be no binding to interfere with the free movement of the arms upon their pivots. The ends of the arms opposite the guides 41 are turned inwardly to form abutment portions 47 for engagement with the under side of the base 5. The parts are so proportioned that when the abutments 47 engage the underside of the base the guides 41 are held in a position with their tray supporting flanges horizontal.

The tray is dished to a proper depth throughout its central portion and about each of its ends it is flanged downwardly 60 slightly as indicated at 48 and its longitudinal edges are extended downwardly and slightly inwardly to provide flanges 49 which make a convenient means of grasping the tray for the purpose of withdrawing it 65 from the guides 41. The tray is symmetri-

cal and accordingly may be reversed so that no care need be exercised as to which side of the tray is inserted first. It is properly positioned with respect to the openings in the base by the engagement of its rear corners 70 with stops 50 which are applied to the horizontal flanges of the guides 41.

The guides 41 retain their normal position through gravity, but when the stove is disassembled the guides may be swung within 75 the base as illustrated in Fig. 4 to render the base more compact for storage and shipment. This obviates the need of removing the guides from the base for said purposes. Furthermore, the guides are thus protected 80 against deformation through rough handling in moving or shipment or by having undue weight imposed upon them during storage; and also by having the guides permanently connected to the base, the possibility of inexperienced persons wrongly mounting or assembling them is avoided.

The importance of having the guides foldable into the base is better appreciated when it is explained how the stove is prepared for 90 shipment. The legs 3, pan 2, and burner tray 40 are removed, leaving the top, base, back and end panels together, and the legs, pan and tray are wired to the back. Therefore, in the knocked down structure, the base 95 is the lowest part (see Fig. 4) and if the guides protrude therefrom, they would be liable to become bent or otherwise damaged.

In Fig. 11 the part 16^a of the burner support is shown as having its front end turned 100 downwardly and connected to the flange that extends along the front side of the opening in the base. Consequently there is no tendency for any oil which may run down the support to flow onto the top surface of the base, but the oil will more naturally follow the down turned end of the part 16^a or the flange to which said end is connected and drop therefrom to the tray below. Accordingly the deflector 20 may be omitted from 110 this style of support.

Having thus described my invention, what I claim is:

1. In a stove structure, in combination with a base having an opening and a burner situated above said opening, guides disposed beneath the base, and a tray slidably supported by the guides beneath the said opening.

2. In a stove of the character set forth, a base having an opening and a burner situated above said opening, guides movably carried by the base, and a tray slidably supported by the guides beneath said opening of the base, the guides normally occupying 125 an extended position but being shiftable to a retracted position.

3. In a stove of the character set forth, a base having an opening and a burner situated above said opening, tray supporting 130

- means movably carried by the base, and a tray removably supported by said means beneath said opening of the base, the supporting means normally occupying an extended 5 operative position but being shiftable to a retracted position.
4. In a stove of the character set forth, in combination, a base having an opening and a burner situated above said opening, 10 tray supporting means hingedly connected to the base and normally depending in operative position therebelow, a tray removably supported by said means beneath the opening of the base, the said tray supporting 15 means being shiftable to a more compact position with respect to the base, as and for the purpose specified.
5. In a stove of the character set forth, the combination of a base having front and 20 rear depending portions, the base being provided with an opening, and a burner situated above said opening, tray supporting members spaced apart longitudinally of the base, said members having extensions, pivotal 25 connection between the extensions and the base, and a tray supported by the members beneath the opening of the base.
6. In a stove of the character set forth, the combination of a base having depending 30 portions at its front and rear sides, the base being provided with an opening, a burner situated above the opening, tray supporting members spaced apart longitudinally of the base, each member having end extensions 35 that are provided with apertures, screws extended through the depending portions of the base and entering the apertures in said extensions thereby to pivotally connect the members to the base, nuts applied to the 40 screws for clamping them to the base extensions, said nuts being interposed between the depending portions of the base and said extensions, and a tray supported by the members beneath the opening of the base.
- 45 7. In a stove of the character set forth, the combination of a base having depending portions at its front and rear sides, the base having an opening, a burner situated above said opening, guides beneath and 50 spaced apart longitudinally of the base, the guides having end extensions that are provided with bearing apertures intermediate their ends, pivot members projecting inwardly from the depending portions of the base and within the bearing apertures of 55 said extensions, the ends of the extensions remote from the guides engaging a part of the base to sustain the guides in operative position, and a tray supported by the guides 60 beneath the opening of the base.
8. In a knock-down stove, the combination of a structure involving a top and a base and means connecting them together and spacing them apart, the base having an 65 opening, a burner supported above the open-
- ing, legs removably connected to the structure for supporting the same with the base a suitable distance above the floor, tray supporting members carried by the base and normally depending therebelow, and a tray 70 removably sustained by said members below the base, the members being retractable above the bottom plane of the base as and for the purpose specified.
9. In a knock-down stove, the combination of a top, a base having a peripheral depending flange and provided with an opening, members connecting together and spacing apart the top and base, legs removably connected to the base for supporting it 75 at a suitable elevation, a burner supported above the opening of the base, tray supporting members movably carried by the base and normally depending below the plane of the lower edge of said peripheral flange, a 80 burner tray removably supported by said members, the members being retractable within the base as and for the purpose specified.
10. In a stove structure of the character set forth, the combination of a base having an opening and a depending peripheral flange, a burner supported above said opening, tray supporting members spaced apart longitudinally of the base and having end 85 branches disposed inside opposed portions of the peripheral flange, means extended through said portions of the flange and whereon the branches of said members are pivoted, and a burner tray removably supported by the members.
11. In a stove structure of the character set forth, the combination of a base having an opening, a burner supported above said opening, guides movably connected to the 90 base and spaced apart longitudinally thereof, a tray slidable upon the guides to a position beneath the opening of the base, and stops carried by the guides for so positioning the tray, the guides normally depending below the base and being retractable 95 to a position above the bottom plane of the base, as and for the purpose specified.
12. In a stove structure of the character set forth, involving a base, the base having an opening, a burner supported above said opening, guides depending below and spaced apart longitudinally of the base, and a tray having end portions arranged to slide upon the guides and having at its front and rear 100 edges means for withdrawing the tray from the guides, the tray being substantially symmetrical and therefore reversible as to its position with respect to the base.
13. In a stove structure of the character set forth the combination of a base having an opening, a liquid fuel burner, and means sustaining said burner above the opening of the base, said means including a support 105 which has its upper end connected to the 110
14. In a stove structure of the character set forth the combination of a base having an opening, a burner supported above the opening of the base, and means including a support 115 which has its upper end connected to the 120
15. In a stove structure of the character set forth the combination of a base having an opening, a burner supported above the opening of the base, and means including a support 125 which has its upper end connected to the 130

burner and its lower end connected to the base, the support incorporating deflecting means for diverting any oil which drains from the burner down said support through 5 the opening of the base.

14. In a stove structure of the character set forth the combination of a base having an opening, a tray removably supported beneath the base and below said opening, 10 a liquid fuel burner, means sustaining the burner above the opening of the base, said means including a support made up of top and bottom overlapped sections and having its upper end connected to the burner and its 15 lower end connected to the base and a deflector inserted between the sections of the support for diverting any oil which drips from the burner along said support into the tray, thereby to prevent said oil from 20 reaching the base.

15. In a stove structure of the character set forth involving a base, the base having an opening, a burner supported above said opening, guides depending below and spaced 25 apart longitudinally of the base, and a tray having end portions arranged to slide upon the guides and having depending flanges along its front and rear edges which constitute means for withdrawing the tray from 30 the guides, the tray being substantially symmetrical and therefore reversible as to its position with respect to the base.

16. In a stove structure of the character set forth, the combination of a base having 35 an opening, a tray removably supported beneath the base and below said opening, a liquid fuel burner, and means sustaining

the burner above the opening of the base, said means including a support having its upper end connected to the burner and its 40 lower end connected to the base and incorporating a deflector for diverting any oil which drips from the burner along said support into the tray, thereby to prevent said oil from reaching the base. 45

17. In a stove structure of the character set forth the combination of a base having an opening, a tray removably supported beneath the base and below said opening, a liquid fuel burner, and means sustaining 50 said burner above the opening of the base, said means including a support which has its upper end connected to the burner and its lower end connected to the base in such manner that any oil which drains from the 55 burner along said support is diverted into the tray and prevented from reaching the top surface of the base.

18. In a stove structure of the character set forth the combination of a base having an opening that is flanged along one side, a tray supported below said opening, a liquid fuel burner, and means sustaining the burner above the opening of the base, said means including a support having its upper 60 end connected to the burner and its lower end turned downwardly and secured to the aforesaid flange whereby any oil which drains from the burner down said support will be diverted to the tray and prevented 65 from reaching the top surface of the base. 70

In testimony whereof, I hereunto affix my signature.

LEE S. CHADWICK.
